ANODE TARGET

Michael J. Zunick, Greenfield, and Howard W. Goodrick, Brookfield, Wis., assignors to General Electric Company, a corporation of New York

Application August 18, 1951, Serial No. 242,466

25 Claims. (Cl. 313—29)

1

The present invention relates in general to electronics and has more particular reference to electron targets, more especially targets for use in electron flow devices such as X-ray generators.

An X-ray generator commonly comprises an assembly of elements including an electron emitter, an electron target, conventionally comprising a block or plate of metal, such as tungsten, and a sealed envelope enclosing the emitter and the target, the assembly commonly being referred to as an X-ray tube. X-rays are produced in such a tube by applying electrical potential for electron driving purposes between the emitter and the target to thus constitute the emitter and the target, respectively, as a cathode and an anode. The so applied potential is thus made effective to impel, toward the anode target, electrons emitted at the cathode, X-rays being generated at the target as a result of electron impingement thereon.

Impingement of electrons on the anode target results in the generation of substantial quantities of heat which, especially in high power tubes, tends to deteriorate and ultimately to destroy the target element. In the interests of efficient X-ray production, the generator tube is usually operated under conditions producing high temperatures in the target short of the melting temperature of the target material. Various expedients are employed for cooling the anode target in order to hold the same at a temperature, during operation of the tube, safely below a temperature at which the target becomes damaged or "burned." Presently available expedients for cooling X-ray tubes, and particularly the anode elements thereof, impose limitations upon the electrical loadings under which the device may be safely operated, since it is necessary to dissipate approximately 95% of the energy which is applied to the tube, for the operation thereof. This energy has to be dissipated from within the relatively thin layer of metal which constitutes the target, and such heat energy, especially in a tube designed for continuous operation, must be removed as rapidly as it is generated as, otherwise, the target will reach a temperature approaching or exceeding the melting temperature of its constituent material, thus resulting in destruction of the target and failure of the tube. Tungsten is presently considered to be the best available target material, the same being most highly resistant to deterioration at the high temperatures imposed by electron bombardment at high intensity. As a consequence, for optimum performance, X-ray tubes embodying tungsten

5

targets are commonly designed for operation under the maximum loadings allowed by the limits of the physical characteristics of tungsten targets.

Commercial X-ray tubes employ either water, oil, or air, as media for the transfer of heat away from the target. To this end, the cooling medium is commonly delivered continuously through a chamber formed behind the target, the medium being circulated between the chamber and an external cooler so that heat may be absorbed from the target into the medium and then extracted from the medium at the cooler. Water and oil have relatively low boiling points and relatively poor heat storing capacity, which limits their effectiveness for heat absorbing and transferring purposes.

An important object of the present invention is to provide an improved electron target from which heat may be readily dissipated.

Another important object is to utilize metal in liquid condition for electron target purposes; a further object being to employ liquid mercury as an electron target.

Another object is to use any metal having relatively low melting temperature as a liquid electron target; a further object being to employ lead, bismuth, thallium, sodium, potassium, lithium, tin and like metals, or alloys thereof, in liquid condition, for electron target purposes.

Another important object is to provide for continuously circulating the liquid metal from target forming position to cooling means, in order to continuously extract from the liquid metal the heat generated therein through use thereof as an electron target.

Another important object is to provide an anode target for X-ray generation comprising means, substantially transparent to X-rays and electrons, forming a container for a metal in liquid condition, whereby to retain the liquid metal in position to serve as an electron target; a further object being to provide for circulating the metal in liquid condition through the chamber and thence to a cooler in order to maintain the liquid target material at a desired operating temperature.

Another important object resides in providing a new method of generating X-rays by causing electrons to impinge upon the surface of a body of liquid metal to constitute the same as an X-ray generating anode.

The foregoing and numerous other important objects, advantages and inherent functions of the invention will become apparent as the same is

50

55

more fully understood from the following description which, taken in connection with the accompanying drawings, discloses preferred embodiments of the invention.

Referring to the drawings,

Fig. 1 is a side view of an X-ray generating tube having an anode target structure embodying the present invention;

Fig. 2 is an enlarged sectional view illustrating the anode target structure shown in Fig. 1;

Fig. 3 is a sectional view illustrating a modified anode target structure embodying the present invention; and

Figs. 4, 5, 6 and 7 are sectional views taken substantially along the line 4—4 in Fig. 3 illustrating various shapes in which the anode target may be formed.

To illustrate the invention, the drawings show an X-ray generating tube 11 comprising a cathode 12 embodying an electron emitting element 13, an anode 14 forming an electron target, and a sealed and evacuated envelope structure 15 enclosing and supporting the anode and cathode in spaced apart facing relationship within the tube.

While the invention is not necessarily limited to any particular form, construction or configuration of the envelope 15, or of the cathode 12, the envelope, as shown more particularly in Fig. 1, may comprise a glass portion 16 at the cathode end of the tube, the cathode 12 being suitably mounted upon the closed end of the glass portion 16. The emitter element 13 may comprise a filament suitably supported in the cathode structure 12, and provided with leads extending outwardly of the envelope through suitable lead seals, such leads being connected with terminal members 17 whereby the filament may be electrically connected with a suitable external source of electrical power in order to energize the filament for electron emission.

The envelope 15 may also comprise a tubular metal portion 18 disposed in axial alignment with respect to the glass portion 16, said tubular portion forming the anode end of the envelope and carrying the anode target structure 14 at the end of said tubular portion remote from the cathode. Any suitable means may be provided for securing the tubular portion 18 with the glass portion 16. To this end, the envelope as shown 50 may include a plurality of glass sections 19 and intermediate metal sections 20 sealingly secured together and to the sections 16 and 18 in end-to-end abutting relationship, said metal portions 20 serving to support metal sleeve members comprising electron lenses 21, in spaced apart axial alignment with the envelope, in position between the emitter 13 and the anode target structure 14.

It will, of course, be understood that the generator tube 11 may be caused to function for the production of X-rays, at the target structure 14, by energizing the emitter 13 for electron emission, as by connecting the terminals 17 with a suitable source of emitter energizing power, while simultaneously applying an electron driving potential between the cathode and the target structure, as by connecting the tube 18, with which the target structure is electrically connected, and one of the cathode connected terminals 17 with a suitable source of electron driving potential. The lens elements 21 may be electrically biased with respect to the emitter, for the control of electron flow between the cathode and the anode, as by applying control poten-

tials between the lens mounting rings 20 and one of the emitter connected terminals 17.

Electrons thus emitted at the cathode may be guided and focused by the lenses 21 to form a beam of electrons 22 directed toward the anode target structure 14. Such electron beam will generate X-rays, at the said anode target structure, as the result of electron impingement thereon. X-rays thus generated at the target structure may be emitted thence as an X-ray beam 22' outwardly of the envelope as through an X-ray transmitting window 23 formed in the envelope.

The present invention broadly contemplates the utilization of metal in its liquid phase for anode target purposes, especially in X-ray generator tubes; and the inventive concept includes the formation of the anode as an open pool of liquid metal enclosed within the sealed envelope, as well as the provision of means for circulating, from a source disposed outwardly of the sealed envelope, a cooling medium in heat exchange relation with the liquid metal in the enveloped enclosed pool. It is, however, more expedient and practical to enclose the liquid metal in a container having a wall of material, such as beryllium, highly permeable to electrons exposed within the sealed envelope, rather than to present the same as an open pool within the envelope. The electron beam generated at the cathode and accelerated in the evacuated envelope will easily penetrate the beryllium wall and bombard the liquid metal itself as an electron target. An advantage which results from thus enclosing the liquid metal in a container is that the liquid metal need not be maintained under the vacuum conditions which necessarily prevail within the sealed envelope. This permits the liquid metal of the target to be circulated continuously through the pool where it serves as an electron target, and to and from suitable cooling equipment outwardly of the envelope. As it passes the zone of electron bombardment, the liquid metal will become heated; however, as rapidly as it is heated, it will be replaced by liquid metal in cool condition, the hot liquid passing to the cooling equipment for extraction of the heat therefrom and subsequent recirculation to the target zone. The material of the liquid metal container, at the target zone, will of course also be heated to some extent but will be held at a safe temperature by the continuous circulation of cooled liquid metal to the container.

The heat load capacity of a liquid metal target, of the sort herein contemplated, is limited only by the velocity at which it can be made to flow past the target area. In theory there is no limit to the energy that may be applied to the target and liberated therein as heat, so long as the liquid metal is caused to flow past the target fast enough to absorb the heat at a rate sufficient to keep the material of the chamber walls from melting and the liquid anode metal from vaporizing.

Mercury is the preferred metal since it has high density, high atomic number, and is readily handled as a liquid at normal atmospheric temperatures and pressures. Metals such as bismuth, lead, tin, thallium, lithium, sodium, potassium, and the like and alloys of such metals may also be employed provided that the tube in which used is operated at an anode temperature above the melting temperature of the metal anode medium, and if suitable means is also pro-

vided for maintaining the metals in fused condition, or for draining them from the anode structure when the X-ray tube is not in use.

The present invention thus contemplates an anode target structure 13 providing means for supporting a mass or pool of metal target material in liquid condition in position such that a surface of said pool may form an anode target surface for the impingement thereon of electrons, the invention further contemplating means for continuously cooling the liquid metal, as by circulating the same between the target structure and suitable cooling means for the extraction of operating heat therefrom, and the consequent removal of such heat from the generating tube, along with the circulating liquid metal. To these ends the target structure may comprise chamber or conduit forming means 24 disposed at the anode end of the envelope and providing a chamber or container for supporting a pool of liquid metal in position, in the generator tube to function as an anode target.

As shown more particularly in Fig. 2 of the drawings, the chamber forming means 24 may comprise a chambered member 25 adapted to be sealingly secured in the end of the tubular envelope portion 18 as by welding, brazing or otherwise sealing the end edges of said tubular portion, as at 26, in a peripheral groove 27 formed in the member 25. The member 25 also may be formed with a central bore or channel forming a chamber 28 opening at the opposite ends of the member 25, said member at one end being formed with an annular seat 29 for the sealing reception of a preferably cup-shaped cover cap 30 in position closing that end of the chamber 28 which faces into the tubular portion 18 of the envelope. The member 25 preferably comprises material which is inert to hot mercury or other liquid target forming substance. To this end, iron, nickel, molybdenum, or alloys thereof may be employed, ferrous alloys containing nickel being especially suitable. The cap or cover 30 is formed of beryllium, or other material highly permeable to electrons and X-rays. The member 30 may be sealingly secured on the member 25, in the seat 29, by brazing the parts together with a layer 31 comprising a suitable bonding material, such as nickel, that is inert to the hot target forming substance. It will be seen that the end of the chamber 28 remote from the cover member 30 opens outwardly of the member 25 at the end of the tubular envelope portion 18. A preferably removable closure member 32 may be provided for normally covering the open end of the chamber 28, whereby to adapt the same to retain a metal in liquid condition as a pool extending immediately behind the cover element 30. The closure member 32 may comprise a plate sealed in position on the member 25 as by means of bolts 33 and a gasket 34. Conduits 35 and 36 may extend in the closure plate 32 in order to provide for circulating liquid metal into and out of the chamber 28, the conduits 35 and 36 being sealed in the closure plate 32. The conduit 36 may extend through the plate 32 and into the cavity 28, preferably centrally thereof, with the end of the conduit opening within and directly behind the cover member 30. The other conduit 35 may open through the plate 32 directly into the chamber 28 at the end thereof remote from the cover member 30. These conduits 35 and 36 may extend to and communicate with suitable cooling apparatus whereby the anode metal in cooled liquid condition may be delivered through the

conduit 36 immediately behind the cover member 30 and displace previously delivered liquid from the chamber 28 through the conduit 35 to the cooling apparatus.

From the foregoing it will be seen that the structure provides a body or pool of liquid metal immediately behind the cover member 30. Such pool has a surface defined by said cover member in position to receive the impact of electrons delivered from the cathode, the enclosing cover member 30 being substantially transparent or pervious to the so delivered electrons. The surface of the pool, defined by the member 30, thus forms an anode target which, when subjected to electron impingement may be constituted as a source of X-rays. Since the member 30 comprises material that is also substantially transparent to X-rays, any rays developed at the surface of the pool, as the result of electron impact thereon, may pass thence through the member 30, as at the sides thereof, for emission laterally of the envelope portion 18, as through the X-ray window 23.

As shown in Figs. 3-7, the present invention is susceptible of embodiment as an exceedingly simple structure merely comprising a tube or pipe 30' disposed in the envelope portion 18 in position exposed to electrons emitted by the cathode 12. This tube 30' preferably comprises beryllium, or other material substantially transparent to X-rays and electrons. The tube 30' may be mounted in diametrically disposed openings formed in the envelope portion 18 and suitably sealed in said openings, as by welding or brazing, as indicated at 34'. The opposite ends 35' and 36' of the tube may be connected with cooling and circulating mechanism for the delivery of liquid metal continuously from the cooling mechanism through the tube 30' and thence back to the cooling mechanism. In such a construction the terminal end of the envelope portion 18, behind the tube 30', may be provided with a cover 32' suitably sealed to the end of the envelope portion 18, as by welding or brazing the parts together as at 26'. As indicated in Figs. 4-7, the portions of the tube 30' disposed within the tubular portion 18 of the envelope may have any desired or preferred cross-sectional configuration, including the circular, oval and rectangular shapes shown; and where the sectional shape is other than circular, as shown more particularly in Fig. 6 of the drawings, the tube may be mounted at any desired inclination in order to disperse X-rays, generated at such inclined target element, outwardly of the X-ray tube in a desired direction. Where the anode structure comprises a tube 30' mounted diametrically of the envelope portion 18, as shown in Figs. 4, 5 and 7, it will be seen that X-rays may be emitted at opposite sides of the envelope, as through windows 23 and 23'.

If desired, supplementary cooling means may be provided, the same comprising means for circulating a cooling fluid, such as oil, water, or the like, in heat exchange relationship with the anode end of the X-ray tube. Such means, in a structure of the sort shown in Fig. 2 of the drawings or in a structure embodying an open pool of liquid in the X-ray tube envelope may comprise ducts or channels formed in the liquid metal containing member, in heat exchange relationship with the liquid metal therein, and including means for circulating a cooling fluid between external cooling apparatus and such cooling conduits formed in the member 25.

As shown in dotted lines in Fig. 3, however, the supplementary cooling means may comprise a preferably sheet metal jacket structure 37 sealed upon the anode end of the envelop portion 18, such jacket means providing an inlet and outlet conduit 39 communicating with the chamber 38 for the circulation of a cooling fluid in heat exchange relationship with the anode end of the X-ray tube, including the anode structure 14 comprising the pipe 30', the jacket including means 40 for sealing the jacket around the opposite ends of the pipe 30' outwardly of the envelope portion 18.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. An anode comprising a member providing a cavity having a wall of material substantially transparent to electrons and a metal in liquid condition in said cavity and forming an electron target behind said wall.

2. An anode comprising a member providing a cavity having a wall portion of beryllium, and a metal in liquid condition in said cavity and forming an electron target behind said wall.

3. An anode comprising a tubular conduit member having a wall of material substantially transparent to electrons, and means to circulate a metal in liquid condition in said tubular member in position forming an electron target behind said wall.

4. An anode comprising a tubular conduit member of circular sectional shape having a wall of material substantially transparent to electrons, and means to circulate a metal in liquid condition in said tubular member in position forming an electron target behind said wall.

5. An anode comprising a tubular conduit member of rectangular sectional shape having a wall of material substantially transparent to electrons, and means to circulate a metal in liquid condition in said tubular member in position forming an electron target behind said wall.

6. An anode comprising a tubular conduit member of elliptical sectional shape having a wall of material substantially transparent to electrons, and means to circulate a metal in liquid condition in said tubular member in position forming an electron target behind said wall.

7. An anode comprising a member providing a cavity having a wall of material substantially transparent to electrons, a metal in liquid condition in said cavity and forming an electron target behind said wall, cooling means remote from said anode, and means forming metal circulating conduits interconnected with said cavity and with said cooling means for the circulation of liquid metal to and from the cooling means through said cavity.

8. An anode comprising a container having a wall of material substantially transparent to electrons and means to circulate metal in liquid condition continuously through said container to provide a body of liquid metal behind said wall in position to serve as a target for electrons delivered through said wall.

9. An anode comprising a container embody-

ing a relatively thin wall portion of beryllium and means to deliver metal in liquid condition continuously behind said wall portion in position to serve as a target for electrons delivered through said wall portion.

10. An anode comprising a container embodying a wall of beryllium, liquid cooling means remote from said container, and means to circulate metal in liquid condition from said cooling means continuously through said container and back to said cooling means to provide a body of liquid metal behind said wall in position to serve as a target for electrons delivered through said wall.

11. An anode comprising a metal member providing a cavity having an open end therein, a relatively thin plate of metal transparent to electrons sealed at its edges in said opening, and means to circulate a liquid metal medium continuously in said cavity and behind said plate in position to serve as a target for electrons delivered through said plate.

12. An anode comprising a metal member providing a cavity having an open end therein, a relatively thin plate of beryllium sealed at its edges in said opening, and means to circulate a liquid metal medium continuously in said cavity and behind said plate in position to serve as a target for electrons delivered through said plate.

13. An anode comprising a container having a wall of material substantially transparent to electrons, means to circulate metal in liquid condition continuously through said container to provide a body of liquid metal behind said wall in position to serve as an electron target, and auxiliary cooling means for circulating a cooling fluid in heat exchange relationship with said container, to cool the same and the liquid metal circulating therein.

14. An X-ray tube embodying a cooperating anode and cathode enclosed in a sealed envelope, said anode comprising a member providing a cavity having a wall of material substantially transparent to electrons and a metal in liquid condition in said cavity and forming an electron target behind said wall.

15. An X-ray tube embodying a cooperating anode and cathode enclosed in a sealed envelope, said anode comprising a member providing a cavity having a wall of material substantially transparent to electrons, cooling means, and means to circulate a metal in liquid condition to and from said cooling means and through said cavity in position forming an electron target behind said wall.

16. An X-ray tube embodying a cooperating anode and cathode enclosed in a sealed envelope, said anode comprising a member providing a cavity having a wall of beryllium, and a metal in liquid condition in said cavity in position providing an electron target behind said wall.

17. An X-ray tube embodying a cooperating anode and cathode enclosed in a sealed envelope, said anode comprising a tubular conduit member having a wall of material substantially transparent to electrons, and means to circulate a metal in liquid condition in said tubular member in position forming an electron target behind said wall.

18. An X-ray tube embodying a cooperating anode and cathode enclosed in a sealed envelope, said anode comprising a tubular conduit member of circular sectional shape having a wall of material substantially transparent to electrons, and means to circulate a metal in liquid

condition in said tubular member in position forming an electron target behind said wall.

19. An X-ray tube embodying a cooperating anode and cathode enclosed in a sealed envelope, said anode comprising a tubular conduit member of rectangular sectional shape having a wall of material substantially transparent to electrons, and means to circulate a metal in liquid condition in said tubular member in position forming an electron target behind said wall.

20. An X-ray tube embodying a cooperating anode and cathode enclosed in a sealed envelope, said anode comprising a tubular conduit member of elliptical sectional shape having a wall of material substantially transparent to electrons, and means to circulate a metal in liquid condition in said tubular member in position forming an electron target behind said wall.

21. An X-ray tube embodying a cooperating anode and cathode enclosed in a sealed envelope, said anode comprising a metal structure providing a cavity, and a pool of metal in liquid condition in said cavity in position forming an anode target, and means to circulate a cooling fluid in heat exchange relationship with said structure and the liquid metal in said cavity. 25

22. An X-ray tube embodying a cooperating anode and cathode enclosed in a sealed envelope, said anode comprising a container having a wall of material substantially transparent to electrons and means to circulate metal in liquid condition continuously through said container to provide a body of liquid metal behind said wall in position to serve as a target for electrons delivered through said wall.

23. An X-ray tube embodying a cooperating anode and cathode enclosed in a sealed envelope, said anode comprising a container having a wall of beryllium, liquid cooling means outwardly of said envelope, and means to circulate metal in 40

liquid condition continuously from said cooling means through said container and back to the cooling means, whereby to provide a body of liquid metal behind said wall in position to serve as a target for electrons delivered through said wall.

24. An X-ray tube embodying a cooperating anode and cathode enclosed in a sealed envelope, said anode comprising a container embodying a relatively thin wall portion of beryllium and means to deliver metal in liquid condition continuously behind said wall portion in position to serve as a target for electrons delivered through said wall portion.

25. An X-ray tube embodying a cooperating anode and cathode enclosed in a sealed envelope, said anode comprising a metal member providing a cavity having an open end therein, a relatively thin plate of metal transparent to electrons sealed at its edges in said opening, and means to circulate a liquid metal medium continuously in said cavity and behind said plate in position to serve as a target for electrons delivered through said plate.
